UNITED STATES PATENT OFFICE.

EDUARD WORRINGEN, OF COLOGNE, GERMANY.

DISTRIBUTING APPARATUS FOR LIGHTING GAS-FLAMES AT A DISTANCE.

SPECIFICATION forming part of Letters Patent No. 783,494, dated February 28, 1905.

Application filed June 21, 1904. Serial No. 213,464.

To all whom it may concern:

Be it known that I, EDUARD WORRINGEN, residing at Cologne, Germany, have invented a new and useful Distributing Apparatus for 5 Lighting Gas-Flames at a Distance, of which the following is a full and complete specification.

The apparatus in question is a feed and turning-off motion for such distance gas-lighters as have a body placed on the gas-pipe, this body being supplied with angle-shaped channels and a revolving ratchet-wheel for regulating the gas. This wheel *s*, which is affixed to the body *a* and which is furnished with 10 pins or teeth *z*, is actuated by a pawl *c*, which is pivoted on a lever *h*, which is in its turn actuated by a spring *f*, which may be moved by hand or air pressure or electricity in the usual manner.

15 Figure 1 shows the distributing and lighting contrivances applied to an incandescent burner which is given in longitudinal section. Figs. 2 to 11 show varying applications of the feeding wheel or disk *s* and of the body *a*.

20 In the apparatus as constructed in Figs. 2 and 3 the regulator *s* consists of a hollow drum or disk, which has on one side a feed slot or groove *e* for the gas, annular in shape and communicating with the feed-passage *k*.

25 There are also a number (in the present instance six) of evenly-distributed exit holes or openings *o* made in the same side of disk *s* as groove *e*. Above the angle-formed feed-passages *k* there are two exit-pipes *l* and *l'*, 30 one of them feeding the full flame and the other the bead or fine flame. The distance between the outlets of the pipes *l* and *l'*, which are under the drum *s*, is half that between the holes *o*. In consequence on a forward movement, which is always equal to half the distance between the holes *o*, one of the latter is 35 put into communication with the pipe *l*, while the pipe *l'* is closed, and on the next forward movement the reverse takes place, the pipe *l* being closed and *l'* opened and the bead left 40 burning, having lighted itself on the full flame before it went out, or the full flame is left burning, lighted by the bead before going out. It will be seen that by simply turning 45 the regulating-drum the lighting-flame can be

turned out or lighted without the bead burning while the full flame is alight.

The arrangement shown in Fig. 7 works in the manner just described, and shown in Figs. 2 and 3, with this difference that the exit-holes *o* in the drum are not connected with the passage *k* and with each other by means of a hollow space or cavity, but by a groove system *n*, formed on one side of disk *s*, as represented in section in Fig. 4.

The construction shown in Figs. 5 and 6 works in the same manner; the annular portion of the groove *n*, as shown in Fig. 7, being done away with. To compensate for this, there are two feed-passages *k* and *k'*, the distance between which is the half of that between the openings *o*. On each one-twelfth of a turn of the drum *s* the passages *k* *k'* come alternately into juxtaposition with the holes *o*, and consequently into communication with the groove *n*. In the same manner the passages *l* *l'* communicate alternately with the holes *o*, so that the lighting and thin flames are fed. The two passages *k* and *k'* could also be replaced by a pipe or other passage of a suitable width. The revolving drum or regulator enables a part of the lights—for example, the jets in street-lamps—to be lighted or turned out earlier than others.

In the forms shown in Figs. 8 to 11 it is 80 presumed that there is a bead-flame burning continually the gas for which does not pass disk *s*, but is fed separately to the bead-flame. The revolving portions *s* of the individual lamps are in the constructions shown in Figs. 85 8 and 9 so arranged that their grooves are set at different angles. In this manner there are always two of the holes *o* *o'* connected by the groove *n*, one close to the other. In the position shown in Fig. 8 one of the openings *o'* is fed by the passage *k*, the gas passing from 90 such passage through opening *o'*, groove *n*, to the opposite opening *o'*, and through pipe *l* to the burner. In Fig. 9, on the contrary, the gas enters through one of the openings *o* *o'* and passes to the burner through groove *n*, opposite opening *o* *o'* and pipe *l*. When 95 the revolving portion *s* of both burners is moved evenly through one-sixteenth of a complete rotation, two opposite openings *o* *o'* of 100

the disk *s* (shown in Fig. 8) will register with passage *k* and pipe *l*, respectively, so as to supply the burner with gas, while passage *k* and pipe *l* of the disk *s* (shown in Fig. 9) are closed. At the next turn of disk *s* through the angle above stated the gas will also be shut off from the burner controlled by disk *s* of Fig. 8, so that both burners are extinguished. At the next turn of the disks the burner fed by disk *s* of Fig. 9 is first supplied with gas through openings *o'*, while the other burner remains cut off, and so on.

In the construction shown in Figs. 10 and 11 there is in Fig. 11 a passage *k'* on the right 15 of the center line. When the regulators take up the positions indicated in Figs. 10 and 11, both burners are fed. If the regulator is turned a one-twelfth to the left, only the passages *k* and *l* of the burner controlled by the 20 disk *s* in Fig. 10 remain open, while pipe *l'* of the burner controlled by the disk *s* in Fig. 11 is closed. On turning the apparatus further the whole of the canals *k*, *k'*, and *l'* are closed. On the next following turn the disks 25 take up their positions as shown and the two flames are fed.

Having now fully described my invention, what I claim as new, and desire to secure by Letters Patent, is—

1. A gas-burner having a gas-inlet and a 30 gas-outlet, combined with a pivoted disk having a groove adapted to communicate with the inlet, and openings for connecting the groove with the outlet, substantially as specified.

2. A gas-burner provided with a gas-inlet 35 and a pair of gas-outlets, combined with a pivoted disk having a groove for connecting the inlet with either of the two outlets, substantially as specified.

3. A gas-burner provided with a gas-inlet, 40 a pair of gas-outlets, and a grooved disk communicating with the gas-inlet and having on one side a series of openings communicating with the groove and adapted to register with the outlets, substantially as specified. 45

Signed by me at Cologne, Germany, this 4th day of June, 1904.

EDUARD WORRINGEN.
